U.S. Cl. D34—15

Fig. 3

Fig. 4

FIG. 1 is a rear perspective view of a toy truck showing my new design; and

FIG. 2 is a front perspective view thereof; and

FIG. 3 is a rear perspective view of another embodiment of FIGS. 1 and 2 wherein a dump-type body is shown in place of a "van"-type body; and

FIG. 4 is a fragmentary elevational view of the front cab portion common to both embodiments of the design showing the tilt-top in an open position.

The bottom of all embodiments is essentially plain and unornamented.

I claim:

The ornamental design for toy truck, as shown and described.
